UNITED STATES PATENT OFFICE.

HERBERT CADY BLODGETT, OF KALAMAZOO, MICHIGAN, ASSIGNOR TO DOOR CONTROL COMPANY, OF HARTFORD CITY, INDIANA, A CORPORATION OF INDIANA.

AUTOMATIC ELECTRIC DOOR CONTROL.

Application filed February 12, 1928. Serial No. 27,831.

The object of this invention is to provide an electrically operated mechanism for the opening and closing of doors or gates, either of the rolling or swinging type, conveniently placed push buttons or switches enabling the operator to open and close the doors or gates with a great saving of time and labor. The use of push buttons or switches is not a part of my invention.

10 My invention relates to an improvement in door or gate controls, in which the control unit is secured to the door or gate. A stationary rope or cable, along which the control unit moves, gives the desired movement for the operation of swing or rolling doors or gates.

I attain this control movement by the mechanism illustrated in the accompanying drawing, in which:

20 Fig. 1 is a vertical section of the entire device, a sliding door being indicated by broken section.

Fig. 2 is a wiring diagram of the structure.

25 The parts of the drawing will be identified by their numerals, which are the same in both views.

30 1 is the main bracket or support providing a suitable base. 2 is an induction electric motor supplying power to the unit. 3 is the motor pinion on the motor shaft. 4 is the main driving gear meshing with pinion 3. 5 is the friction driving pulley which is opposed to the idler V-grooved pulley 6. The pulleys 5 and 6 embrace the rope or cable 7, the ends of which are connected to the door post at each side of the door where they are secured to brackets 33 by suitable set screws 31. The idler pulley 6 is carried on pivoted arm 8 which is supported on the pivot stud 9 which permits up and down movement. The pulley 6 is journaled on the stud 10 and is disposed in opposition to the pulley 5 carried by the gear 4. A spring 11 compresses the arm 8 and is adjusted by the adjusting screw 12 which regulates the pressure between the V pulleys 5 and 6. By adjusting the screw 12 pressure is applied to these friction pulleys causing them to engage the rope or cable 7. 13, 13 are fair leading tubes or guides secured to the main bracket 1 for guiding the structures upon the cable 7 when the complete unit is moving along said rope or cable. The cable 7 being supported by its ends on the door posts or frame and being disposed near the path of the door in its to and fro opening movement, is engaged frictionally by the pulleys 5 and 6 which are advanced along the cable and thus open or close the door by carrying the unit which is attached thereto back and forth. The pulleys of course engage the rope or cable by friction and yield sufficiently to permit the same to revolve in the event the switch fails to cut out the motor, and will yield for instance if there should be a person or vehicle in the path of the door when it is closing, or opening either, for that matter.

35 14 is a cut-out switch body. 15 is the sliding switch rod of non-conducting material which is adapted to reciprocate in and project outwardly at either end of the cut-out switch body 14. The switch rod 15 is provided with retaining disks 16, 16 for the purpose of engagement of the compression coil springs 17, 17 for imparting movement to the said rod. The rod 15 cooperates with the adjustable stop 32 which is screw threaded into the bracket 33, above referred to. 18 is a metal band of conducting material on the rod 15 constituting a switch member. It is flush with the surface of rod 15 so that it will readily reciprocate through the switch. Carbon brushes 19, 19 are on opposite sides of the switch and located with an easy moving fit at right angles to the switch rod 15. The inner ends of the carbon brushes 19 are concave and conformed to the contour of the rod 15. This provides for a large contact surface for conducting the electric current when the switch is closed. When the switch rod 15 is in central position the contact 18 is between the carbon brushes 19, thus forming an electrical contact for the passage of current. When the switch rod 15 is forced to the position shown in the drawing, the metal band 18 is out of contact with the carbon brushes, thus disconnecting the electric current. Flat springs 20, held in position by the retaining screws 21, hold the carbon brushes 19 yieldingly in place. 21 are binding screws which serve to attach the power leads 22 so that the current from the source of supply is properly conducted through the flat spring 20 to and from the carbon brushes 19.

40 23 is a reverse switch body which is made

of non-conducting material. The reversing mechanism is to properly conduct the current from the source of supply to the field windings and rotating armature of the motor 2, so that the desired direction of rotation of the motor will be obtained. 24 is the switch rod of non-conducting material which reciprocates in the reverse switch body 23. 25, 26 are metal bands of contact conducting material arranged in the form of stationary rings upon the switch rod 24. These rings are let in flush with the rod 24 so that the same may reciprocate readily through the switch body. The projecting ends of the rod 24 contact with the adjustable stops 30 in the bracket 33 at each end and are consequently controlled by the movement of the controller back and forth. 26, 26 are carbon brushes which are concave to fit perfectly the contour of the switch rod 24. 27, 27 are flat springs held in position by retaining screws 28, 28, to hold the carbon brushes 26, 26 yieldingly in position, thus insuring perfect electrical contact.

25 I have illustrated five pairs of carbon brushes 26, but for a complete reversal only four are necessary, some motors which require five being practically obsolete at the present time. By shifting the contacts 25, 30, 25, it is very clear that the motor can be reversed.

29, 29 are the power leads which are controlled by this switch. Flexible cable is provided to permit the movement of the controller, so that no sliding contacts are necessary. The door is indicated in broken section at 34 to which the bracket 1 is secured in any suitable way, the same being indicated in suitable section. Only one end and one side of this structure have been illustrated, but the opposite end and side are symmetrical and would be lettered and numbered the same. That is to say, at the opposite end of the travel of the door is a second bracket or support 33 with adjustable stops. Whether the door is a sliding or swinging door is a matter of no consequence.

50 The operation of the structure is as follows: A switch, as a push button, is closed which starts the motor. As soon as the motor starts from the position indicated in the drawing, the right hand spring 17 reacts, moving the switch rod 15 to the central position, closing the circuit independent of the push button and maintaining the circuit closed throughout the course of its travel or until the current is cut out. This admits the current through the appropriate brushes 26, 26 and contact 25 of the reversing switch, 55 which is set to start the motor and carry the reversing unit with the door to the open position. When the unit reaches the open position the left hand cut-out switch rod 15 contacts with the appropriate stop and cuts out

the current and at the same time the left 65 hand end of the reverse switch rod 24 contacts with its stop 30 and carries the switch to the reverse position.

It will thus be seen that the structure, after starting with the push button and the 70 releasing of the push button, will automatically stop and that if the push button is held down, owing to the fact that the motor is an induction motor, the motor will continue to run and the friction pulleys will 75 slip on the rope until the motor is stopped by opening the switch; then when the switch is closed the motor will reverse and close the door.

These operations are repeated indefinitely. 80 Because there is a friction connection between the pulleys and the cable which is adjustable, the tension on the same can be such that if the door strikes an obstacle the friction pulleys will slip and the action of the 85 door will not be so positive as to be dangerous.

I claim:

1. In an electrically operated door or gate control, an electric motor, a connection and 90 support therefor on the said door or gate, friction drive pulleys carried by said support and gear connection to the said motor to drive one of the pulleys, a flexible traction connection supported adjacent the path of 95 said door engaged by the said friction device, a slideable cut-out switch carried by the motor support, stops for actuating the same at each end of the travel of said door or gate, and a slideable reversing switch carried by 100 the said motor support with stops for shifting the same at the end of the travel of said door or gate, and a manually controlled switch to start the action, as specified.

2. In a door actuating means, the combination of a motor with suitable support on the said door, stationary traction connections disposed along the path of said motor, gear connections from said motor to the said 105 stationary connections, a cut-out switch carried by said support and operated by suitable stops at the end of said door travel, a reversing switch carried by said support with stops for actuating the same and reversing it at the end of said door travel to 110 reverse the motor, and a manually controlled switch for initiating the action of said motor, as specified.

3. In an electrically operated door or gate control, an electric motor, a connection and 120 support therefor on the said door or gate, friction drive means connected to said motor, a traction connection supported adjacent the path of said door engaged by the said friction drive, a cut-out switch carried by 125 the motor support, stops for actuating the same at each end of the travel of said door, a reversing switch carried by the said motor

support with stops for shifting the same at the end of travel of said door, and a control switch to start the action, as specified.

door adapted to yield and permit the motor to run when the door in its travel is stopped by obstruction or final stop, as specified. 10

4. In a door actuating means, the combination of a motor with support on the said door, friction connections from said motor with coacting means for actuating the said
